ELECTRIC CIRCUIT BREAKER

Arnold Haller and Hans Thommen, Baden, Switzerland, assignors to Aktiengesellschaft Brown Boveri & Cie, Baden, Switzerland, a joint-stock company of Switzerland

Application January 23, 1936, Serial No. 60,362
In Germany January 30, 1935

12 Claims. (Cl. 200—148)

This invention relates in general to improvements in electric circuit breakers and more particularly to circuit breakers of the fluid blast type in which the functions of interrupting the flow of current in a circuit, and of thereafter maintaining the circuit open, are performed by separate contacts.

In the operation of circuit breakers of the fluid blast type, the current interruption takes place under the most advantageous conditions when the arcing contacts are rapidly separated to a distance permitting the flow of a lateral blast of fluid of maximum velocity between the contacts, the circuit being opened permanently by means of disconnecting contacts which are opened after the arc has been extinguished and while the fluid blast is still being maintained. To obtain a proper relationship between the operating speeds of the arcing and disconnecting contacts, separate actuating means are preferably provided therefor, and means, which may include interlocks, are provided for insuring the sequential operation of the arcing and disconnecting contacts. Such an arrangement, which comprises in effect two complete separate switching devices, may lead to the disadvantage of a design requiring a considerable amount of space and involving an excessive cost.

Such disadvantages are obviated by actuating the two switching devices by fluid pressure operated means, and by solidly connecting the movable arcing contact of the circuit breaker with one of the disconnecting contacts thereof. The arc drawn between the arcing contacts is blown into a deionizing chamber for preventing an excessive extension thereof. Means are preferably provided for insuring immediate reclosure of the arcing contacts upon opening of the disconnecting contacts, and for insuring the complete operation of the disconnecting contacts after initiation of such operation. The disconnecting contacts may also be caused to close in air under pressure higher than atmospheric pressure to reduce arcing which may occur while the contacts are approaching engagement. The arcing and disconnecting contacts may also be normally bridged by current carrying contacts if the circuit breaker is to carry relatively large currents. The actuating mechanism for the disconnecting contacts preferably includes a latched yieldable linkage permitting the breaker to open immediately after it is caused to close on an overload or short circuit.

It is therefore one of the objects of the present invention to provide a circuit breaker of the

fluid blast type which overcomes the above stated disadvantages and which is of simple construction and reliable in operation.

Another object of the present invention is to provide a circuit breaker of the fluid blast type in which a disconnecting contact is rigidly fastened to a movable arcing contact of the breaker.

Another object of the present invention is to provide a circuit breaker of the fluid blast type in which arcing and disconnecting contacts are sequentially operated by separate mechanisms operable at predetermined speeds.

Another object of the present invention is to provide a circuit breaker of the fluid blast type having a disconnecting contact actuated by a fluid pressure operated motor provided with means for insuring complete operation of the contact.

Another object of the present invention is to provide a circuit breaker of the fluid blast type provided with a mechanism permitting the circuit breaker to open immediately after it is caused to close on a faulty circuit.

Objects and advantages other than those above set forth will be apparent from the following description when read in connection with the accompanying drawings, in which:

Fig. 1 is a side elevational view of a circuit breaker built in accordance with the present invention and provided with an electro-responsive relay for mechanically causing operation of the circuit breaker upon flow of excessive current therethrough;

Fig. 2 is an enlarged axial cross section through the arcing chamber of the embodiment illustrated in Fig. 1 taken in a plane parallel to the plane of projection utilized in Fig. 1;

Fig. 3 is a partial cross section taken along plane III—III in Fig. 1 to illustrate the disconnecting contacts of the circuit breaker;

Fig. 4 is a partial cross sectional elevation through a modified embodiment of the deionizing chamber illustrated in Fig. 1;

Fig. 5 is a cross section taken along plane V—V in Fig. 4;

Fig. 6 is a cross sectional view similar to that shown in Fig. 5 through another modified embodiment of the deionizing chamber illustrated in Fig. 1;

Fig. 7 diagrammatically illustrates in detail the disconnecting contact actuating means and the preferred system of control applicable to the embodiment illustrated in Fig. 1;

Fig. 8 is a cross sectional view similar to Fig. 3 but differing therefrom in that one of the con-

tacts is provided with a reinforced portion for interlocking the arcing and disconnecting contacts;

Fig. 9 is an elevational view, partially in cross section, of disconnecting contacts differing from the contacts illustrated in Fig. 1 in the addition of a latch for interlocking the arcing and disconnecting contact;

Fig. 10 is a side elevational view, partially in cross section, illustrating disconnecting contacts of the sliding tubular type which are caused to approach mutual engagement in air at a pressure higher than atmospheric pressure;

Fig. 11 diagrammatically illustrates a portion of the modified control system differing from the system illustrated in Fig. 7 in that fluid is supplied to the arcing chamber of the breaker for a predetermined length of time during each operation of the breaker;

Fig. 12 is a partial side elevational view, partially in cross section, of a circuit breaker provided with bridging contacts across the arcing and disconnecting contacts;

Fig. 13 is a partial side elevational view, partially in cross section, of a circuit breaker differing from the embodiment illustrated in Fig. 12 in having one of the disconnecting contacts thereof pivoted on the movable bridging contact; and

Fig. 14 diagrammatically illustrates a portion of another modified control system applicable to the control of the modification illustrated in Figs. 12 and 13.

It will be understood that elements illustrated in some of the figures may also be utilized in combination with elements illustrated in others of the figures to form further embodiments of the invention.

Referring more particularly to the drawings by characters of reference, Fig. 1 illustrates a circuit breaker including as a constructive element thereof a reservoir 16 constituting a source of supply of fluid under pressure, which will be assumed herein to be compressed air, supplied from a suitable compressor (not shown) through a pipe 17 for maintaining the pressure within the reservoir at a substantially constant value. Reservoir 16 is supported on any suitable base, such as a framework 18 of structural steel adapted to be bolted on a wall. Although in general circuit breakers of the type herein considered are provided with a plurality of similar switch elements to be inserted in the several conductors of an electric circuit, only one such element is shown in Fig. 1 and the circuit breaker will be described in detail as if it were of the single pole type. The circuit breaker comprises an arcing chamber 19 supported on reservoir 16 through a hollow insulator 21, which also serves to admit air under pressure from reservoir 16 into the chamber. In general it is preferred to form chamber 19 of metal but it will be understood that such chamber may also have walls at least partially of insulating material and may then also constitute a prolongation of insulator 21. The metallic walls of chamber 19 constitute one of the terminals of the circuit breaker, and a line conductor may be bolted directly thereon or may be connected therewith through an electroresponsive relay 22 operable to cause opening of the circuit breaker upon flow of excessive current therethrough.

As shown in Fig. 2, a detachable portion or cover 23 of chamber 19 is provided with an orifice about which is arranged an annular contact 24 constituting the fixed arcing contact of the circuit breaker. The cooperating movable arcing con-

tact 26 is mounted on a piston 27 arranged for reciprocatory movement within a cylinder 28 arranged coaxially with contact 24. Cylinder 28 is fastened to an insulating liner 29 of chamber 19 serving to insulate contact 26, piston 27 and cylinder 28 from contact 24 when the arcing contacts are open. Cylinder 28 is partially closed at the upper end thereof by a diaphragm 31 provided with apertures for regulating the admission of air from chamber 19 within cylinder 28. Piston 27 is thus rendered operable by means of fluid under pressure introduced within chamber 19 adjacent contacts 24 and 26 for separating such contacts. The contacts cooperate in normally closing the orifice of chamber 19, contact 26 being urged into engagement with contact 24 by resilient means such as a spring 32 acting between contact 26 and chamber 19 through diaphragm 31. Although the circuit breaker is shown as having only one pair of arcing contacts, it will be understood that a plurality of serially connected pairs of arcing contacts could also be provided in separate arcing chambers, the movable contact of each pair being urged by a spring acting against such contact and the associated chamber. A spring acting between two oppositely directed movable contacts severally operable by fluid pressure would allow the contact offering the least frictional resistance to open, while the contact offering the greater frictional resistance would remain closed.

The orifice of chamber 19 communicates with an extension of cover 23 forming a nozzle 33 leading into a deionizing chamber 34. Such chamber is preferably frusto-conical in shape having a wall 35 constituted of a metal sheet wound to form a spiral convolute surface. The convolutions of wall 34 thus offer a path of comparatively large cross section to the flow of air therethrough and oppose only a comparatively small resistance thereto, while presenting a large surface for cooling and deionizing such air and for separating therefrom metallic particles detached by the arc from the arcing contact. Chamber 34 also effectively reduces the report caused by the circuit interruption. The air issuing from the outer fold of wall 34 is preferably directed upward away from grounded or current-carrying members of the circuit breaker by a cylindrical shield 36. The construction of chamber 34 may also be rendered somewhat simpler by making the chamber of uniform cross section as illustrated in Fig. 4, wall 34 then being made from a rectangular sheet wound spirally about a cylindrical surface. It may also be advantageous to provide several parallel channels for the flow of air issuing from nozzle 33, and wall 34 may accordingly be constituted of a plurality of interleaved spirally wound sheets as shown in Fig. 6.

Piston 27 is provided with an extension carrying one of the contacts 37 of a disconnecting switch, the arcing and disconnecting contacts being serially connected by the rigid conductive connection between contacts 26 and 37 through piston 27. Contact 37 is preferably formed as a pair of laminated brushes cooperating with another disconnecting contact 38, the space surrounding the cooperating surfaces of contacts 37 and 38 being confined by an insulating shield 39. Contact 38 is formed as a twin blade of which the two halves are spread and pivoted on either side of a bracket 40 forming the second terminal of the circuit breaker, and supported on reservoir 16 by means of an insulator 41 similar to insulator 21. Contact 38 is extended beyond the

5 pivot thereof to form the lever pivotally joined to a connecting rod 42 of insulating material actuated by a crank 43 of a shaft 44 supported for rotary movement on reservoir 16. Shaft 44 is 10 preferably actuated by fluid pressure, such shaft receiving movement from a piston 45 shown in Fig. 7 and arranged for reciprocatory movement within a cylinder 46 through a connecting rod 47 and a double crank 48 to thereby disengage contact 38 from contact 37. Another piston 49 within a cylinder 50 acts on shaft 44 through a connecting rod 51 and crank 48 for engaging contact 38 with contact 37. The movement of shaft 44 and of pistons 45 and 49 may be retarded when the pistons approach the ends of their stroke by means of a pair of dashpots 52.

10 Fig. 7 also diagrammatically illustrates all three switching elements of a three pole circuit breaker. The connection between connecting rod 51 and crank 48 is effected through a link 53 pivotally connected therebetween to thus form a yieldable linkage. A spring 54 tends to maintain rod 51 and link 53 in alinement, the action of such spring being limited by abutment of the lower end of rod 51 against a projection of a latch 56. The latch is mounted on crank 48 and normally engages the lower end of connecting rod 51 to prevent lateral yielding of the joint of rod 51 and link 53 under the action of piston 49. When the circuit breaker is in the closed position as shown in Fig. 7, contacts 37 and 38 being engaged, latch 56 is disengaged by abutment thereof against a stop 57 which may be arranged on an extension of connecting rod 47.

15 Cylinder 50 is generally in communication with the atmosphere through a valve 58, and may be supplied with air under pressure from reservoir 16 through the valve upon actuation thereof by a lever 59. Lever 59 constitutes the armature of an electromagnet 61 and is actuated upon connection of the magnet coil with a suitable source of current such as a battery 62. Such connection may be effected through contacts 63 of a manually operable control switch 64. The circuit breaker may be opened by connecting the coil of a second electromagnet 66 with battery 62 through contacts 67 of switch 64 and through a segment of an auxiliary drum switch 68 actuated by shaft 44. Electromagnet 66 is provided with a lever armature 69 for actuating a second valve 71 similar to valve 58. Valve 71 controls the admission of air under pressure from reservoir 16 into a cylinder 72 containing a piston 73 acting against the action of a spring 74. Piston 73 actuates a pilot valve 75 controlling the admission of air under pressure from reservoir 16 into a second cylinder 76 containing a piston 77 acting against a spring 78 and actuating a main valve 79. Valve 79 controls the admission of air from reservoir 16 into arcing chamber 19 and into cylinder 46 for causing sequential operation of pistons 27 and 45. The connections between valve 79 and cylinder 46 may include means such as a needle valve 81 for controlling the speed of the flow of air to cylinder 46 to delay the action of piston 45.

20 The piston rods associated with pistons 45 and 49 extend above cylinders 46 and 50 and are shaped with cam surfaces engaging with a pair of followers 82, 83 and maintain the followers in the position shown when the pistons are at either end of the stroke thereof. The cam surfaces also allow the followers to engage the associated levers 59, 69 during substantially the entire stroke of the piston to thereby maintain valves 68 and 71 in the respective positions thereof. Such arrangement

25 insures the completion of the stroke of the pistons after initiation thereof even if switch 64 is moved during such operation. Switch 64 may be provided with contacts 84 cooperating with switch 68 to control a visual signal lamp 86, and may also be provided with contacts 87 cooperating with switch 68 in controlling an auditory signal such as a horn 88.

30 Assuming the circuit breaker to be in the closed position shown in Figs. 2 and 7, if it is desired to cause the circuit breaker to open, switch 64 is momentarily brought to the position indicated "to trip". A circuit is thus completed from battery 62 through contacts 67, switch 68 and coil 66 back to the battery. Electromagnet 66 accordingly attracts the armature 69 thereof, thus causing operation of valve 71. Valve 71 admits air under pressure from reservoir 16 into cylinder 72, and piston 73 is thereby moved downward to open pilot valve 75. Valve 75 admits air into cylinder 76, 20 which has a greater diameter than valve 79, and piston 77 is accordingly moved downward and opens valve 79. Air under pressure is thus simultaneously admitted into arcing chamber 19 for causing operation of piston 27 and for blowing out 25 the arc drawn between the arcing contacts through the orifice of chamber 19, and into cylinder 46. Although the contact disengaging operation of piston 27 and of piston 45 is thus initiated simultaneously, operation of piston 45 for 30 opening contact 38 must be prevented until after complete opening of contact 26 by piston 27 and extinction of the arc drawn at the arcing contacts has taken place. Such result may be obtained solely by suitable choice of the relative weights of 35 the members to be actuated, or the operation of piston 45 may be delayed and the speed thereof adjusted by the provision of valve 81 for regulating the rate of admission of air from reservoir 16 into cylinder 46, whereby piston 45 is caused to 40 move slowly relatively to the speed of operation of piston 27.

35 When air is admitted into chamber 19, the orifice of such chamber is closed by the associated arcing contacts and the pressure rapidly increases 45 within the chamber about the arcing contact and within the space adjacent piston 27. The mass of piston 27 and of contacts 26 and 37 carried thereby is relatively very slight and the piston rapidly moves downward to separate contacts 24 and 26 50 at a predetermined speed depending upon the dimensions of the apertures in diaphragm 31. An arc is accordingly drawn between contacts 24 and 26, and such arc is violently blown, by the blast of 55 compressed air flowing in chamber 19, radially toward the orifice thereof, i. e. transversely with respect to the arc path. The maximum separation of contacts 24 and 26 is so chosen as to cause the velocity of the air blast to reach a maximum 60 value within the space adjacent the contacts, and the dimensions of the orifice and of nozzle 33 are so chosen as to cause the arc to be extinguished upon the first passage of the arc current through the value zero when the circuit breaker is utilized 65 in an alternating current circuit. The blast of air is heated by the arc, is rendered conductive by ionization therefrom and also carries metallic particles removed from the arcing contacts. The hot air reaching nozzle 33 and chamber 34 expands substantially adiabatically therein and thus reaches a materially lower temperature. The air temperature is further decreased by contact of the air with the convolutions of wall 34, the air 70 also being deionized and stripped of the metallic 75

particles carried thereby by contact thereof with wall 34.

During such operation, contact 37 is moved downward by piston 27 in sliding engagement with contact 38, but contact 38 remains stationary until after interruption of the arc at the arcing contacts. Reignition of the arc at the arcing contacts is prevented by the continuous blast of air present therebetween, and an arc 10 cannot be established between chamber 19 and cylinder 31 as a result of the large arcing distance therebetween along insulating liner 29. All flow of current through the circuit passing through the breaker is thus interrupted, but such 15 circuit must be opened by disconnecting contact 38 because the air blast may not be maintained indefinitely between contacts 24 and 26 and, even if such contacts were maintained separated, the distance therebetween would generally be too 20 small to prevent flashover therebetween upon interruption of the air blast.

At substantially the time of interruption of the arc between the arcing contacts, the air pressure within cylinder 46 has reached a sufficient 25 value for causing piston 45 to be actuated to cause disengagement of contacts 37 and 38. Upon initiation of the movement of piston 45, crank 48 driven thereby may move link 53 and connecting rod 51 as a single member, although such members then form a yieldable joint, because cylinder 30 is then in communication with the atmosphere and thus does not oppose the movement of piston 49 therein. A slight movement of the crank 48 disengages stop 57 from latch 56, which then engages connecting rod 51 and thus restores a rigid 35 linkage between crank 48 and piston 49. Followers 82 and 83 operate in response to movement of pistons 45 and 49 to maintain armatures 59 and 69 and valves 58 and 71 in the respective positions 40 thereof to thereby insure completion of the stroke of the pistons.

When the disconnecting contacts have become fully opened, the gap therebetween is sufficient 45 to maintain open the circuit controlled by the circuit breaker, and the arcing contacts may then be reclosed by interruption of the supply of air under pressure to cylinder 28. For this purpose, while piston 45 is completing its stroke, switch 68 opens the circuit of magnet coil 66. At substantially the end of the stroke of piston 45, follower 50 83 returns to the position shown and releases armature 69, which is then no longer attracted by coil 66. Valve 71 then returns to the position shown to place cylinder 46 in communication with the atmosphere, whereby piston 45 remains in the position it has reached corresponding to full opening of disconnecting contact 38. Cylinder 72 is also brought into communication with the atmosphere, and pilot valve 55 75 closes, permitting the air in cylinder 76 to leak out through apertures provided for such purpose. Valve 79 returns to the closed position and ceases to admit air under pressure to chamber 19, and the air within such chamber escapes 60 through the orifice thereof, whereupon spring 32 causes reengagement of the arcing contacts. Switch 68 also completes the circuit of lamp 86 thus indicating that the operation of the circuit breaker is then complete. Switch 64 may then 65 be moved into the position marked "open", whereby the circuit of lamp 86 is again opened. Switch 64 may however not be moved into the position marked "closed" as such movement would cause lamp 86 again to be lit.

70 Tripping of the circuit breaker may be obtained

automatically in response to the flow of excessive current through the breaker by means of an overload relay 89 operable to close a pair of contacts bridging contacts 67. Such automatic tripping may also be obtained by means of relay 22, (not shown in Fig. 7) which actuates valve 71 mechanically in response to the flow of excessive current to the circuit breaker. Upon any automatic opening of the circuit breaker while switch 64 remains undisturbed, switch 68 completes the 10 circuit of lamp 86, which indicates that the circuit breaker has operated. Switch 68 also completes the circuit of alarm signal 88. By moving switch 64 into the position marked "open", contacts 84 are opened, whereby lamp 86 becomes 15 dark, and the latched connection between the spindle of switch 64 and the segment joining contacts 87 becomes unlatched, whereby contacts 87 are opened and alarm signal 88 ceases to function.

If the circuit breaker is open, closure thereof may be initiated by moving switch 64 into the position marked "to close". Such movement causes closure of contacts 63, which connect magnet coil 61 with battery 62. Valve 58 is thus 25 actuated and admits air under pressure from reservoir 16 into cylinder 50. Connecting rod 51 and link 53, which are then rigidly latched, transmit the movement of piston 49 to crank 48, completion of such movement being insured by 30 the action of followers 82 and 83 which operate in response to movement of pistons 45 and 49 to maintain valves 58 and 71 in their respective 35 positions during substantially the entire stroke of the pistons. Contact 38 is closed by shaft 44 and, the associated arcing contact being already closed, the circuit is completed at the engaging surfaces of contacts 37 and 38. A flashover may then occur between such contacts while they are approaching mutual engagement, but such flashover is usually without detrimental effect as the resulting arc generally carries only current within the normal current carrying capacity of the circuit breaker and is rapidly terminated by engagement of the disconnecting contacts. An extension of the arc from the disconnecting contacts to other elements of the circuit breaker is 40 prevented by shield 39 which confines the space where such arc is produced.

Upon completion of the closure of the circuit breaker, switch 68 completes the circuit of lamp 86 which indicates that the circuit breaker has 50 operated. Switch 64 may then be moved back into the position marked "closed", thereby opening the circuit of lamp 86 and also establishing 55 the latched connection by which the segment associated with contacts 87 may be moved into the position shown, whereby alarm signal 88 may be operated upon subsequent automatic tripping of the circuit breaker. Such latched connection is broken when switch 64 is moved into the position marked "to trip" in order to avoid unnecessary operation of alarm signal 88.

If the circuit breaker is closed as above described and the flow of current therethrough immediately reaches an excessive value, as occurs when the breaker is closed on a short circuit, relay 89 or relay 22 immediately cause operation of valve 71 while valve 58 is still admitting air into cylinder 50. Piston 49 is accordingly maintained in the position shown by the air pressure within cylinder 50, and pistons 27 and 45 are actuated in the manner above described to disengage the arcing and disconnecting contacts. This operation is possible for the reason that, at the 70 75

moment of full closure of contact 38, connecting rod 51 is disengaged from latch 56. The air pressure acting on piston 45 is transmitted by connecting rod 47 and crank 48 to link 53, the joint between link 53 and connecting rod 51 yielding to move connecting rod 51 sideward against the action of spring 54. A latching of connecting rod 51 by latch 56 is then no longer possible, and piston 45 may complete its stroke to cause opening of the circuit breaker, which thereafter remains in the open position. Upon return of switch 64 to the position marked "closed", alarm signal 88 operates, thereby indicating automatic tripping of the circuit breaker. Such movement of switch 64 also causes deenergization of magnet coil 61 which releases valve 58, whereupon cylinder 50 is put in communication with the atmosphere and piston 49 is moved upward under the action of spring 54 to the uppermost position thereof, at which position connecting rod 51 re-engages latch 56. Switch 64 is then moved into the position marked "open" to interrupt the circuits of lamp 86 and of alarm signal 88.

If it is not desired to rely on the operating characteristics of the contact actuating means for causing sequential operation of the arcing and disconnecting contacts, an interlock may be provided therebetween. As shown in Fig. 8, the portion of contact 38 normally engaging with contact 37 when the circuit breaker is closed may be made of materially greater thickness than the immediately adjacent portion. The operating means for contact 38 are then so dimensioned that when the arcing contacts are closed, and contact 37 is accordingly in the position shown, it is impossible for piston 45 to move contact 38 out of engagement from contact 37 against the frictional resistance present therebetween. Piston 27, on the contrary, is so dimensioned that upon admission of air from reservoir 16 into chamber 19 such piston may open the arcing contact and move contact 37 downward out of engagement with the reinforced portion of contact 38. Upon completion of such movement, contact 38 no longer offers any resistance to the action of piston 45 which may move such contact into the open position. Piston 49 is so dimensioned as to be able to reclose contact 38, of which the reinforced portion is beveled, into engagement with contact 37. Such closure is facilitated by the momentum acquired by contact 38 during the closing movement thereof, so that it may be possible to utilize a piston 49 of the same cross section as piston 45.

Fig. 9 illustrates another interlock consisting of a latch 90 pivoted on piston 27 between the two halves of contact 37. When the circuit breaker is in the closed position as shown, the latch engages with a projection of contact 38 and prevents opening of the latter. When piston 27 moves downward to open the arcing contact, latch 90 slides over the projection of contact 38, which may then be opened by piston 45.

Instead of utilizing disconnecting contacts of the pivoted blade and jaw type above considered, contacts of the sliding tubular type may be employed. As shown in Fig. 10, piston 27 may carry a split resilient tubular contact 91 arranged to engage a sliding tubular contact 92. Contact 92 is arranged for longitudinal movement within bracket 40 and may be actuated from shaft 44 through gears 93 and through a pinion 94 engaging with a rack 96 integral with contact 92 or fastened thereon. The mechanism includes a member of insulating material 97. Insulating

liner 29 is preferably extended downward to a material extent to thereby guide the tip of contact 92 in substantially fluid tight relation therewith over a substantial distance. Contact 92 is provided with a diaphragm 98 so that liner 29 forms a substantially fluid tight chamber for the cooperating surfaces of contacts 91 and 92 when such contacts are within a predetermined distance of each other. The air within such chamber is thus brought to an increased pressure during engaging operation of the disconnecting contacts, whereby the dielectric strength of such air is materially increased and arcing between the contacts is thereby prevented until the contacts are closely adjacent each other.

Instead of controlling the closure of valves 75 and 79 by means of auxiliary switch 68, time delay means may be provided for reclosing such valves after a predetermined length of time. As shown in Fig. 11 such means may consist of a piston 73, which is then provided with a port, and of spring 74, cylinder 72 having no communication with the atmosphere. Cylinder 72 receives air from the reservoir 16 through valve 71 as in the embodiment illustrated in Fig. 7, whereby piston 73 is actuated downward to cause opening of valve 75. Valve 75 admits air into chamber 19 and also admits air into cylinder 46 through a check valve 99. Air also passes from one side of piston 73 to the other side thereof through the port of the piston and, after a predetermined time delay, the pressure on the lower side of the piston reaches a sufficient value to enable spring 74 to reclose valve 75, whereby valve 79 is caused to reclose. A direct communication is also provided between valve 71 and cylinder 46 to provide a continuous supply of air to cylinder 46 during the stroke of piston 45. To avoid premature operation of piston 45 upon operation of valve 71, such additional connection is completed through a port in the wall of cylinder 45 which is uncovered by piston 45 after such piston has made part of its stroke under the action of the air supplied through valve 79. Check valve 99 prevents the supply of air from cylinder 46 to arcing chamber 19 after closure of valve 79.

In circuit breakers designed for carrying and interrupting comparatively large currents, it is not always desirable to provide disconnecting contacts and arcing contacts capable of continuously carrying the rated current of the circuit breaker. It is then preferable to provide cooperating fixed and movable contacts for bridging the arcing and disconnecting contacts. As shown in Figs. 12 and 13, the arcing and disconnecting contacts may be bridged by a fixed contact 101 mounted on chamber 19 cooperating with a movable contact 102 pivoted on bracket 40 and actuated by connecting rod 42. Contact 38 may also be pivoted on bracket 40 as shown in Fig. 12, or may be pivoted on contact 102 as shown in Fig. 13. Contact 38 is then actuated by pistons 45 and 49 through contact 102. Contacts 38 and 102 are provided with cooperating surfaces and are maintained in abutment at such surfaces by means of a spring 103. It will be observed that contact 102 may be actuated by piston 45 or piston 49 only while the associated arcing and disconnecting contacts are in engaged position. The operating mechanism of the circuit breaker 70 may then be arranged as shown in Fig. 14. In such figure, valve 71 admits air directly into cylinder 46 to cause movement of piston 45. When the piston has moved a certain distance, contact 102 is opened thereby while contact 38

remains in engagement with contact 37 against the action of spring 103 as a result of the friction between such contacts, or of the presence of an interlock therebetween. Piston 45 then uncovers a port in cylinder 46 for admitting air from cylinder 46 into cylinder 72, whereby the arcing and disconnecting contacts of the circuit breaker are caused to open sequentially, the arcing contacts reclosing immediately upon completion of the stroke of piston 45 under the control of switch 68. The circuit breaker is reclosed by movement of piston 49, which actuates contact 102. Such contact urges contact 38 by means of the cooperating surfaces of contacts 102 and 38 in such a manner that contact 38 recloses before contact 102. Fig. 14 also illustrates a modified form of some of the details of the operating mechanism of the circuit breaker. Spring 54 is shown acting between connecting rods 47 and 51, and stop 57 is shown carried by a fixed member instead of being carried by connecting rod 47. The followers for locking valves 58 and 71 during the stroke of pistons 45 and 49 are shown as rigidly coupled and responsive to movement of piston 45 into the one or the other end position thereof.

Although but a few embodiments of the present invention have been illustrated and described, it will be apparent to those skilled in the art that various changes and modifications may be made therein without departing from the spirit of the invention or from the scope of the appended claims.

It is claimed and desired to secure by Letters Patent:

35. 1. An electric circuit breaker including a plurality of relatively movable arcing contacts, means operable by fluid pressure for actuating one of said arcing contacts, a disconnecting contact in mechanical and conductive connection with said one of said relatively movable contacts, a second disconnecting contact cooperating with the first said disconnecting contact, means operable by fluid pressure independently of said movable arcing contact actuating means for actuating the second said disconnecting contact, means for simultaneously initiating the operation of the first and the second said contact actuating means, and means for preventing operation of the second said contact actuating means until after operation of the first said contact actuating means.
40. 2. An electric circuit breaker including a plurality of relatively movable arcing contacts, means operable by fluid pressure for disengaging said arcing contacts, a disconnecting contact in mechanical and conductive connection with one of said relatively movable contacts, a second disconnecting contact cooperating with the first said disconnecting contact, means operable by fluid pressure independently of said movable arcing contact actuating means for engaging and disengaging the second said disconnecting contact with and from the first said disconnecting contact, means for initiating contact disengaging operation of the first and the second said means, and means for preventing the said operation of the second said means until after operation of the first said means.
45. 3. An electric circuit breaker including a plurality of relatively movable arcing contacts, means operable by fluid pressure for disengaging said contacts, a disconnecting contact in mechanical and conductive connection with one of said relatively movable contacts, a second disconnecting contact cooperating with the first said

disconnecting contact, means operable by fluid pressure for engaging and disengaging the second said disconnecting contact with and from the first said disconnecting contact, means for supplying fluid under pressure to the first and the second said means to cause sequential contact disengaging operation thereof, means responsive to disengaging operation of the second said means for interrupting the supply of fluid under pressure to the first said means, and resilient means for causing reengagement of said arcing contacts upon interruption of the supply of fluid under pressure to the first said means.

4. An electric circuit breaker including a pair of cooperating arcing contacts, a pair of cooperating disconnecting contacts serially connected with said arcing contacts, cooperating fixed and movable contacts for bridging the first and the second said pairs of contacts, and means operable by fluid pressure for actuating said movable bridging contact only when the first and the second said pairs of contacts are in engaged position.

5. An electric circuit breaker including a plurality of relatively movable arcing contacts, means operable by fluid pressure for disengaging said arcing contacts, a disconnecting contact in mechanical and conductive connection with one of said relatively movable contacts, a second disconnecting contact cooperating with the first said disconnecting contact, means operable by fluid pressure for engaging and disengaging the second said disconnecting contact with and from the first said disconnecting contact, means for supplying fluid under pressure to the first and the second said means to cause sequential contact disengaging operation thereof, means responsive to disengaging operation of the second said means for interrupting the supply of fluid under pressure to the first said means, resilient means for causing reengagement of said arcing contacts upon interruption of the supply of fluid under pressure to the first said means, and means for guiding the second said disconnecting contact and forming a substantially fluid tight chamber for the cooperating surfaces of said disconnecting contacts when said disconnecting contacts are within a predetermined distance of each other, whereby the air within said chamber is brought to an increased pressure during engaging operation of said disconnecting contacts.

6. An electric circuit breaker including a supply of fluid under pressure, an arcing chamber carrying an insulated cylinder and having an orifice coaxial with said cylinder, a piston arranged for relatively rapid movement within said cylinder upon admission of fluid under pressure into said chamber, cooperating arcing contacts one of which is mounted about the orifice and the other of which is mounted on said piston, resilient means urging said contacts into mutual engagement to close the orifice, a disconnecting contact arranged on said piston in conductive connection with the arcing contact mounted thereon, a second disconnecting contact cooperating with the first said disconnecting contact, means relatively slowly operable by fluid pressure for disengaging the second said disconnecting contact from the first said disconnecting contact, and means for simultaneously connecting said chamber and said contact disengaging means with the supply of fluid pressure.

7. An electric circuit breaker including a supply of fluid under pressure, an arcing chamber carrying an insulated cylinder and having an

- 5 orifice coaxial with said cylinder, a piston arranged for movement within said cylinder upon admission of fluid under pressure into said chamber, cooperating arcing contacts one of which is mounted about the orifice and the other of which is mounted on said piston, resilient means urging said contacts into mutual engagement to close the orifice, a disconnecting contact arranged on said piston in conductive connection with the arcing contact mounted thereon, a second disconnecting contact cooperating with the first said disconnecting contact, means operable by fluid pressure for disengaging the second said disconnecting contact from the first said disconnecting contact, means for simultaneously connecting said chamber and said contact disengaging means with the supply of fluid pressure, and means for delaying the action of said contact disengaging means.

10 8. An electric circuit breaker including a plurality of relatively movable arcing contacts, means operable by fluid pressure for actuating one of said arcing contacts, a disconnecting contact in mechanical and conductive connection with said one of said relatively movable contacts, a second disconnecting contact cooperating with the first said disconnecting contact, means operable by fluid pressure for actuating the second said disconnecting contact, means for simultaneously initiating the operation of the first and second said contact actuating means, and means for insuring completion of the movement of the second said contact actuating means.

15 9. An electric circuit breaker including a supply of fluid under pressure, an arcing chamber having cooperating arcing contacts, means operable by fluid pressure within said chamber for separating said arcing contact, a disconnecting contact in mechanical and conductive connection with one of said arcing contacts, a second disconnecting contact cooperating with the first said disconnecting contact, a cylinder containing a piston operable by fluid pressure for disengaging the second said disconnecting contact from the first said disconnecting contact, a valve for connecting said chamber and said cylinder with said supply of fluid pressure, another cylinder containing a piston operable by fluid pressure for engaging the second said disconnecting contact with the first said disconnecting contact, a valve for connecting the second said cylinder with said supply, a latched yieldable linkage in the connection between the second said piston and the second said disconnecting contact, and means for unlatching said linkage when said disconnecting contacts are engaged, whereby said connection may yield and the first said piston may disengage said disconnecting contacts when said valves are simultaneously open.

20 10. An electric circuit breaker including a supply of fluid under pressure, an arcing chamber having cooperating arcing contacts, means operable by fluid pressure within said chamber for separating said arcing contacts, a disconnecting contact in mechanical and conductive connection with one of said arcing contacts, a second disconnecting contact cooperating with the first said disconnecting contact, a cylinder containing a piston operable by fluid pressure for disengaging the second said disconnecting contact from the first said disconnecting contact, a valve for connecting said chamber and said cylinder with said supply of fluid pressure, another cylinder containing a piston operable by fluid pressure for engaging the second said disconnecting contact with the first said disconnecting contact, a valve for connecting the second said cylinder with said supply, and means responsive to movement of said piston for maintaining said valve open during substantially the entire stroke of said piston.

25 11. An electric circuit breaker including a supply of fluid under pressure, an arcing chamber having cooperating arcing contacts, means operable by fluid pressure within said chamber for separating said arcing contacts, a disconnecting contact in mechanical and conductive connection with one of said arcing contacts, a second disconnecting contact cooperating with the first said disconnecting contact, a cylinder containing a piston operable by fluid pressure for disengaging the second said disconnecting contact from the first said disconnecting contact, a valve for connecting said chamber and said cylinder with said supply of fluid pressure, another cylinder containing a piston operable by fluid pressure for engaging the second said disconnecting contact with the first said disconnecting contact, a valve for connecting the second said cylinder with said supply, and means responsive to movement of said pistons in response to operation of one of said valves for maintaining said valves in their respective positions during substantially the entire stroke of said pistons.

30 12. An electric circuit breaker including a supply of fluid under pressure, an arcing chamber having an orifice, a pair of cooperating contacts operable to close said orifice, means operable by fluid pressure within said chamber for separating said contacts, valve means for controlling the admission of said fluid from said supply into said chamber to cause operation of said contact separating means and for blowing out the arc drawn between said contacts through the orifice, means for causing opening of said valve means, and time delay means for causing said valve means to reclose.
